INVENTOR.

Albert A. Smallhouse,
BY Stephen S. Mack
ATTORNEY.

UNITED STATES PATENT OFFICE.

ALBERT A. SMALLHOUSE, OF LOS ANGELES, CALIFORNIA.

DESIGN FOR A SMOKING STAND.

Application filed June 27, 1927. Serial No. 22,570. Term of patent 3½ years.

To all whom it may concern:

Be it known that I, **ALBERT A. SMALLHOUSE**, a citizen of the United States, residing at Los Angeles, in the county of Los Angeles and State of California, have invented a new, original, and ornamental Design for Smoking Stands, of which the following is a specification, reference being had to the accompanying drawing, forming part thereof.

In said drawing:

Fig. 1 is a perspective view of the smoking stand, showing the ash receiver in

broken lines so as not to obscure the design on the top;

Fig. 2 is a transverse section of the top of the stand on line 2—2 of Fig. 1.

Fig. 3 is a perspective view of the ash receiver shown in dotted lines in Fig. 1; and

Fig. 4 is a longitudinal section of the ash receiver on line 4—4 of Fig. 3.

I claim:

The ornamental design for a smoking stand, as shown and described.

ALBERT A. SMALLHOUSE.
